UNITED STATES PATENT OFFICE

100,278

DESIGN FOR A PIANO BAR

Kenneth M. Metcalf, Los Angeles, Calif., assignor
to Harry A. Ungar, Inc., a corporation of California

Application March 3, 1936, Serial No. 61,460

Term of patent 3½ years

To all whom it may concern:

Be it known that I, Kenneth M. Metcalf, a citizen of the United States and a resident of Los Angeles, Los Angeles County, State of California, have invented a new, original, and ornamental Design for a Piano Bar, of which the following is a specification, reference being had to the accompanying drawings, forming a part thereof.

Figure 1 is a front perspective of the bar with the cover elements in closed position.

Figure 2 is a front perspective showing cover parts in open position.

Figure 3 is a rear perspective of the bar showing its foot rail in retracted position and the top in closed position.

Figure 4 is a rear perspective of the bar showing its foot rail in extended, lowered position and the top cover in open position.

I claim:

The ornamental design for a piano bar, substantially as shown.

KENNETH M. METCALF.
